UNITED STATES PATENT OFFICE.

LEROY C. DOANE, OF EAST CLEVELAND, OHIO.

ELECTRICALLY-HEATED FLATIRON.

Application filed February 10, 1923. Serial No. 618,236.

To all whom it may concern:

Be it known that I, LEROY C. DOANE, a citizen of the United States, residing at East Cleveland, in the county of Cuyahoga and State of Ohio, have invented a certain new and useful Improvement in Electrically-Heated Flatirons, of which the following is a full, clear, and exact description, reference being had to the accompanying drawings.

This invention relates to improvements in electrically heated devices, particularly flatirons equipped with a circuit controller for automatically maintaining a constant temperature of the iron.

Flatirons equipped with automatic heat controlling devices electrically coupled to the heating element have heretofore been used, but considerable difficulty has been experienced in maintaining a constant temperature without employing complicated control mechanism which is subject to frequent breakage. Usually the controllers have been positioned adjacent the end of the iron where the heat generated from only a portion of the filament can affect the controller. Accordingly, the point where the filament is more or less concentrated would be heated to an excessive degree before the rear portion of the iron would attain sufficient heat to open the controller. Moreover this construction necessitated an odd shape of hood which detracted from the appearance of the iron. Furthermore this results in a distorted iron, whereas an object of this invention is to effect the results with a construction all within the confines of a standard artistic form of iron.

One of the objects of my invention therefore, is the provision of a simple, effective construction of the elements comprising the body of the iron to facilitate production methods and manufacture, while providing a construction which causes the heat of the ironing surface to govern the action of the circuit controller.

My invention also contemplates an arrangement of controller and associated elements whereby the heat in the base of the iron and adjacent the central portion thereof is used for actuating the controller. In this connection, my invention is directed toward a construction which permits the controller to be positioned adjacent the mid-portion of the iron thus enabling the use of

a hood having a smooth uninterrupted surface adjacent the rear of the iron.

Another object is to eliminate any electrical connections carried by the casing or cover of the iron, while at the same time providing for a holder or guide for the cord plug or like connection member removably engageable with the current carrying terminals projecting through the cover.

Other objects will become apparent from the following description, taken in connection with the accompanying drawings, and the essential features will be summarized in the claims.

In the drawings, Fig. 1 is a vertical longitudinal section through an iron constructed according to my invention; Fig. 2 is a view showing the relation of the co-operative parts forming the iron; Fig. 3 is a plan view of an iron having the hood removed, and having a portion of the inner parts broken away to indicate the controller construction; Figs. 4, 5 and 6 are sections on correspondingly numbered lines in Fig. 3 and drawn on enlarged scale; Fig. 7 is a circuit diagram; Fig. 8 is a plan view of the iron; Fig. 9 is a vertical longitudinal section through parts of the iron showing the means for attaching the handle to the hood; and Fig. 10 is a perspective view of the strain and stress distributing member used for attaching the handle to the hood.

My invention in general, embodies a construction which permits the heating element to be readily replaced without replacing an entire iron and also embodies the use of a circuit controller which may be readily positioned within the body of the iron without materially increasing the size thereof. Accordingly, I have illustrated the various parts of the iron as comprising a base 10, a heating plate 11, a body comprising an intermediate plate 12 and a top plate 13, a hood 14, handle supports 15, and a handle 16. Within the iron, I provide a circuit controller electrically coupled in series with the heating element for automatically controlling the temperature of the iron.

The heating element 11 embodies a filament 48 preferably disposed intermediately but insulated from an upper layer of light sheet metal 20, and a lower layer 21. Suitable contact leads 22 and 23 connected with the ends of the filament project upwardly from the rearward end of the sheet 20, as

shown particularly in Fig. 2. These are bifurcated to removably embrace contact screws making a firm connection with current supply parts through the heat responsive controller. By making the heating element in this manner, I obtain a substantially flat plate which is similar in form to the outline of the iron and which may be readily interposed between the base and body members when the iron is assembled. Moreover, this construction permits the elements to be easily and quickly replaced without destroying the iron and without danger of short circuiting the heating filament. I have shown the element as having a centrally disposed rectangular opening 24 whereby the heat imparted to the base acts by convection currents on the controller.

The intermediate plate 12 may comprise a casting, shaped similarly to the base 10 and heating plate 11. An opening 26 similar to the opening 24 in the element extends through the plate for receiving the circuit controller. The side walls 26 of the opening extend beyond the under surface of the plate to form flanges 27, which extend into the element opening 24 and serve to protect the circuit controller from the direct radiation of the heating element.

Superimposed upon plate 12, I provide an upper plate 13 which may also comprise a casting having a recess on the under surface thereof into which the support for the circuit controller is placed. This plate is shown as solid throughout substantially the entire portion thereof, but is well adapted for the reception of an electro-static control device, such as a condenser, whenever desired. Suitable securing members 29 and 30 are illustrated as extending through the superimposed plates and attached to the base 10. When assembled, the plates provide a hollow box-like opening within the middle portion of the iron into which the circuit controller is positioned.

The circuit controller which I prefer to employ embodies as shown in Fig. 3, one contact member 35 which is carried by a rigid bar 36 and another contact member 31 which is carried by a flexible strip 37. The strip 37 is preferably anchored at one end intermediate a thermostatic bar 38 and a support 40 and is shown as provided with an adjustable screw 34 adjacent the free end thereof. When heat is applied, the bar 38 is moved away from the bar 36 whereupon the head of the screw 34 is brought into engagement with the end of the strip 37, thus breaking contact between the points 35 and 31. The members which carry the contact points are disposed in a vertical plane whereby arcing is prevented when the iron is in use. This is advantageous over the use of an iron wherein the strips are disposed in a horizontal plane

because of the fact that the impact of the iron upon the work would tend to separate the contact points, thus causing arcing which quickly destroys the contact points.

The support comprises a block of insulating material 40, which depends within the opening 26 and is suspended intermediate current carrying members 41 and 42, which in turn are electrically connected to current carrying plates 43 and 44 respectively. These plates are suitably insulated from each other and from a housing 45 which holds the plates in operative relation to each other. These plates and the associated housing are shaped to fit snugly within the recess 28 in the cover plate so that the exposed lower face lies in approximately the same plane with the lower face 47 of the plate. This permits the plates 12 and 13 to be brought into close-fitting engagement with each other and aids materially in maintaining an even distribution of heat through the iron.

The contact members 35 and 36 together with the associated contact plates 43 and 44 are electrically connected in series with the heating element 48 as follows:—

Current enters the iron through a terminal post 50, passes through the plate 44, bracket 42, bar 36, contact point 35, contact point 31, strip 37, bracket 41, plate 43, lead 22, filament 48, lead 23, strip 51 and then passes out through terminal post 52.

This construction permits the circuit controller as a unit to be removed from the iron and also permits the heating element to be separately removed for repair purposes without replacement of the entire iron. If desired, the controller may be positioned within the recess by means of the securing screw 30, which functions to hold the cast parts together, but to prevent any possibility of short circuiting, I prefer to secure the controller separately to the top plate 13, as by securing screw members 53, passing through openings, as at 54, Fig. 4.

The method of mounting the cord plug terminal pins 50 and 52 upon the upward extensions of the plate 44, as shown, permits these pins to project through openings in the cover into the terminal plug holder being insulated from the cover by a suitable refractory block 70. The heating element terminals are screwed to downwardly projecting ears 43 and 51, by screws carried by each ear, after the parts are assembled and before placing the cover in position. Thus the plug pins or terminals and the connections are rigid with the means supporting the heat responsive controller and the whole may be easily connected and the parts assembled without the use of flexible connections within the hood, as are usually used and which afford so much difficulty in assembling and in use.

To enable the weight of the iron to be

satisfactorily supported and at the same time to permit the use of a thin shelled hood, I employ a load distributing member 60 which is disposed within the hood adjacent the ends of the handle supports 15. This member 60 is illustrated as a flat strip having the sides struck upwardly, as at 63 and 64, and having the intermediate portions struck upwardly, as at 65 and 66, to 10 provide tongues for receiving the ends of the handle supports. This construction is shown particularly in Figs. 9 and 10 wherein the ends of the handle supports pass through openings in the top of the hood, 15 and then extend around the ends of the member 60. The extreme inner ends of the supports are then positioned intermediate the tongues and the exposed sides of the member. A single screw 67 may then be 20 employed for holding the hood in proper position on the iron.

The plug guide is shown as formed by a strip 80, secured by the handle clamping bolt 82, and having tongues 84 curved outwardly and inwardly from each side of the strip, while the lower end of the strip is secured by a projection 85 through the support 15.

From the foregoing description, it will be 30 seen that my invention provides an iron wherein the heat may be automatically controlled and regulated, and which possesses advantageous features of ease in assembly and replaceability. The relative position of 35 the heating element to the circuit controller and cast parts is such that the controller is protected from the direct rays of the heating filament and yet is embedded within the iron in close proximity to the filament 40 whereby the necessary weight of the iron may be obtained without increasing the size of the iron.

Having thus described my invention, I claim:—

45 1. An electrically heated flatiron comprising in combination, a base, a plurality of body members disposed above the base, a comparatively thin flat heating element having a resistance filament therein, means 50 for removably securing the heating element intermediate the base and one of said members, said element and one of said members having registering openings, a circuit controller electrically coupled to said filament, 55 and means for protecting the controller from the direct rays of the heating filament.

2. An iron having a base and a plurality of superimposed weight members, a heating filament disposed intermediate the base and 60 members, and a circuit controller electrically connected to said filament, said controller being carried by one of said members and positioned within another member but in close proximity to the mid-portion of the filament.

3. In an electrically heated flatiron, the combination with a base member, of a plurality of body members superimposed thereon, one of said members having an opening therein, a heating element, a thermostatic 70 switch positioned above the heating element and extending within said opening, said switch being electrically connected with said element and means for protecting the switch from direct radiation of the element while 75 permitting direct radiation from the base.

4. In combination, a base, a plurality of body members positioned upon the base, an electrical heating element disposed intermediate the base and said members, one of said 80 members having an opening therein adjacent the central portion thereof, a thermostatic switch electrically connected to said element and extending downwardly from one of said members through said opening, 85 said member being so shaped adjacent the controller that the controller is exposed to the heat in said base, but is protected from direct radiation of said element.

5. In a device of the character described, 90 the combination with a base, of an electrical heating element removably positioned thereon, a plurality of body members superimposed on said element, one of said members having an opening adjacent the central portion of the heating element, a circuit controller carried by the other of said members and depending within the opening, said controller being electrically connected to said element, and a baffle disposed intermediate 95 the controller and the element for protecting the controller from the direct rays of the element.

6. In a device of the character described, 100 the combination with a base, of a heating element superimposed thereon, said element comprising a filament, and a housing therefor, said housing having an opening extending therethrough, a plurality of body members superimposed on the element, one 110 of said members having an opening in registration with that in the housing, a circuit controller disposed within the opening in said member, and a flange extending downwardly from said last mentioned member 115 and projecting through the opening in said housing, said flange serving partially to position the element and to protect the controller from the direct heat rays of said element.

7. In an electrically heated flatiron, the combination with a base member, of a plurality of body members superimposed thereon, one of said members having an opening therein, a heating element, a thermostatic 120 switch positioned above the heating element and extending within said opening, said switch having contact members movable in a horizontal plane whereby separation of the contact members with consequent arcing occurs.

4
curing due to impact of the iron with the work is prevented.

8. In an electrically heated flatiron, the combination with a base, of a heating element associated therewith, said element comprising an electric resistance filament, a thermostatic switch electrically coupled to said filament, and positioned above said base, the contact members of said switch being disposed for operation in a horizontal plane whereby arcing is prevented by impact of the iron and work.

9. An electrically heated flatiron comprising a base member, a heating member and a body member above the base member, terminals for the heating element projecting upwardly, a support having downwardly projecting electrical connections carrying means for removably securing said projections directly to said terminals, said support having rigid upwardly extending arms carrying cord terminal plug engaging pins, and means for electrically connecting said pins through the support to said terminals, and a cover for the iron having openings through which the pins project.

10. An electrically heated flatiron having in combination, a base member, a heating element for the base member having upwardly projecting terminals, a heat responsive device governing the current to the heating element and a support for said heat

responsive device, a body member above the base carrying said support, there being downwardly projecting terminal members adapted to be movably and firmly fixed by direct connection, the heating element, terminals and an upward projection from said support carrying the cord plug pins, said support being so arranged that current may pass from one pin through the heat responsive circuit breaker and through the heating element, and then to the other pin, a cover for the iron having openings through which said pins project.

11. In an electrically heated flatiron, the combination of a base member, a heating element for the base member and a body member above the base member, a heat responsive circuit breaker and support therefor, said support including insulating means for electrical connections to and from the circuit breaker of the heating element, and means rigid with the support for carrying upwardly projecting terminal pins, and means projecting downwardly from the support for rigid connection to terminals of the heating element, and a removable cover for the iron through which said terminal pins project.

In testimony whereof, I hereunto affix my signature.

LEROY C. DOANE
